UNITED STATES PATENT OFFICE.

CLYDE A. BARBOUR, JR., OF MONROE, LOUISIANA.

GAS TIP AND PROCESS FOR PRODUCING CARBON BLACK.

Application filed October 1, 1926. Serial No. 139,010.

The present invention relates to the production of carbon black from natural and other gases and has for its object the production of a tip or jet whereby the gas can be burned in a more economical manner with the production of a very much higher quantity of carbon from a given quantity of gas than can be produced by burners now known in the art. A further object of my invention resides in a new and improved process of burning the gases referred to for the production of carbon black wherein the tip or jet herein described is used.

In accordance with the present invention, a thin flat stream of gas capable of yielding carbon black on partial combustion is established. This stream of gas is then ignited and faced on both sides by a stream of atmospheric air or other gas promoting partial combustion. A definite zone of combustion or partial combustion will be established between the two streams and the usual carbon collecting plate or channel iron is positioned near or above this zone. The carbon may be removed from the plate or channel iron in a suitable and known manner.

Referring now to the drawings accompanying this description and forming part thereof, and in which corresponding parts are designated by the same reference numerals—

Figure 1 shows a side elevation view of the tip or jet on an enlarged scale;

Figure 2 shows a similar view, part of which is shown in longitudinal section;

Figure 3 shows a plan view of the tip or jet shown in Figures 1 and 2;

Figure 4 shows a modification of the invention in side elevation, part of which is shown in section;

Figure 5 shows a plan view of the modification shown in Figure 4.

The tip or jet comprises a neck 1, preferably tapered slightly to permit of a tight frictional fitting of the same within the pipe 1', having a bore 2 which leads to the chamber 3. This chamber 3 is provided at its upper end with an opening 4 in the form of a narrow slot across the whole top of the burner. The chamber 3 is separated from each of the two air passages 5 by means of the walls 6 and the outer parts of the passages or channels 5 are bounded by the walls 7. These passages 5 begin near the neck 1 of the tip or jet and extend to the top there-

of, ending in slotted openings 8. The relationship of the two air channels to the remaining parts of the tip will readily be understood upon an inspection of the drawings.

Above the gas tip is placed the carbon collecting plate or channel iron 11 for collecting the carbon. The position of the plate 11 relative to the tip may be adjusted either by raising or lowering the plate or channel iron or by raising or lowering the tip. By such adjustment the plate 11 may very easily be positioned by trial at the point for maximum carbon collection.

The modification shown in Figs. 4 and 5 is similar in all respects with the modification above described except for the provision of a series of small openings 10 which form air passages on both sides of the gas slot.

The tip is made of any suitable material capable of resisting the heat, for example, steatite, ceramic material, or heat resistant metal. The tip constructed in accordance with the present invention is about twice the size of the ordinary tip used in producing carbon black from natural gas and measures about one-half of an inch at its widest part at right angles to the direction of flow of the gas. The height of the tip measuring from the base of the passage 5 is about three-sixteenths of an inch. The size of the passages may be proportioned to correspond in the proportions shown in the drawing; or the gas and air passages may be respectively about one-thirty-second and one-sixteenth of an inch.

Having described my invention, its operation is as follows: The gas from which the carbon black is to be produced enters the bore 2 and proceeds into the chamber 3 to the opening 4 from which it emerges in a stream many times as wide as the length of the slot 4. Upon ignition of the gas, air is sucked or aspirated through the two passages 5 by the flow of the gas and faces the gas. The air does not mix with the gas but will be present at the point of combustion in sufficient amount to support combustion of the gas to any extent desired, as the amount of air and gas can be regulated by changing or varying the size of the air or gas orifices. The relative position assumed by the streams of gas and air are approximately shown in Fig. 2 by means of legends and dotted lines.

2

It will be noted that the air simply makes an enveloping body on each side of the gas. The collecting plate 11 for the carbon is placed at or near the point of combustion of the gas and air as shown clearly in Figs. 1 and 2.

Having described my invention what I claim is:

1. A gas tip or jet with a head having a slot therein for spreading gas as it issues therefrom into a flat mass, means for conducting gas to said slot, said head also having air channels therein which are not in communication with said gas conducting means, said air channels having their outlets positioned on both sides of and near

said slot and extending substantially the whole length of said slot.

2. A gas tip or jet with a head having a slot therein for spreading gas as it issues therefrom into a flat mass, means for conducting gas to said slot, said head also having channels therein which are not in communication with said gas conducting means, said air channels terminating in slots in said head positioned on both sides of and near said first mentioned slot, said last mentioned slots being substantially of the same length as said first mentioned slot.

In witness whereof I have hereunto set my hand.

CLYDE A. BARBOUR, JR.
